ATTORNEY.

UNITED STATES PATENT OFFICE.

GUSTAV J. GRUENDLER, OF ST. LOUIS, MISSOURI.

ICE-BOX.

1,019,631.

Specification of Letters Patent.

Patented Mar. 5, 1912.

Application filed September 7, 1909. Serial No. 516,513.

To all whom it may concern:

Be it known that I, GUSTAV J. GRUENDLER, a citizen of the United States, residing at St. Louis, State of Missouri, have invented certain new and useful Improvements in Ice-Boxes, of which the following is a specification, such as will enable those skilled in the art to which it appertains to make and use the same.

10 The object of my invention is to provide an improved ice-box or refrigerator by means of which access to any of the contents stored therein is readily gained, a further object being to provide an ice-box which permits of greater storage capacity for ice in proportion to its size than ice-boxes heretofore constructed, and still further to provide an ice-box wherein the articles stored therein will be subjected to a greater degree 20 of refrigeration, by means of my ice-receptacles than in the boxes now in use. But that which I believe is the essential feature of my improved ice box lies in the construction and position of the ice-receptacles, into 25 which the ice is introduced.

The invention is fully and clearly described in the following specification of which the accompanying drawing forms a part, in which the separate parts of my improvement are designated by suitable reference characters in each of the views, and in which—

Figure 1 is a perspective view of an ice box constructed according to my invention; 35 Fig. 2, a vertical section thereof taken on line 3—3 of Fig. 1; Fig. 3 a perspective view of one of the ice-receptacles; Fig. 4, a vertical section taken on line 2—2 of Fig. 1.

In the drawing forming part of this specification I have shown an ice-box A, provided with the hinged cover B, and the glass panel C, on top, and the glass paneled, hinged, doors D, in front. Sliding shelves E are provided in the front part thereof, on which 45 the articles to be stored are placed; the sliding shelves extending horizontally, and a trifle upwardly, to the rear of the ice-box, to within close proximity of the ice-receptacles.

F, represents the ice-receptacles extending 50 downwardly from the cover of the ice-box to a certain distance desired above the bottom a, of same.

G represents a removable catch-basin supported on the legs o which rests on the bottom a of the ice-box; this catch-basin is 55 open on top and is provided with small holes

p in the bottom of same. The handles s are provided for removing the catch-basin from the ice-box. This catch-basin is provided for the purpose of securing an easy means 60 of keeping the ice-box in a cleanly and sanitary condition; the melted ice from the ice receptacles, will drip into the catch-basin carrying the dirt and slime from the ice, and will deposit the same into the catch basin, 65 the water escaping through the holes in the bottom of the said catch-basin, it will then be a simple matter to remove the catch basin for cleaning and return same into the ice-box. This arrangement will be a great convenience over the ice-boxes as now constructed which are not provided with the removable catch-basin. Because when such ice-boxes are cleaned the front doors must remain open long enough to do so, thereby 70 subjecting the interior or storage part of the ice-box to the temperature of the outer air, and as is the case of my catch-basin, the front doors would remain open just long enough to remove same from the ice-box; 75 the time required to do so would be much less when compared to the time required to do the same work in the ice-boxes now in use, therefore the cleanliness and economy in using my improved ice-box, is apparent 80 when compared to those now in use.

Into the ice receptacles, the ice (which has been reduced to pieces of a desired size) is introduced, and the melted ice drips from the bottom f of the ice receptacles into the 90 catch-basin G, from which it escapes through the holes o as indicated by the arrows in Figs. 2 and 4, thence to the outlet b.

The sliding shelves E, take up the front 95 part A¹ of the box A, leaving a rear part A², which is occupied by the ice-receptacles F, which may consist of one or a plurality of same, as may be desired. The sliding shelves E, are held in position by, and have freedom 100 of movement between the cleats e, which are secured to the sides of the ice-box in a well known manner.

By opening the doors D, the shelves can be drawn out, partly or entirely, partly, for the purpose of affording easy access to the articles stored thereon, and entirely, for the purpose of cleaning. As hereinbefore stated, the shelves extend rearward to within close proximity of the ice-receptacles F so as 110 to afford as great an amount of storage capacity on the shelves as possible.

The bottom *a* of the ice box is so constructed that the melted ice will drain toward the outlet *b* as shown in Figs. 2 and 4. The other points of construction of the ice box, excepting the ice receptacles are of an ordinary design and are shown only for the purpose of more clearly illustrating my improvement in connection therewith.

The ice-receptacles are constructed as shown in section, in Figs. 2 and 4, and in perspective in Fig. 3, and can be made of different parts integrally connected to each other, or of one piece as may be desired. The shell of the ice-receptacle, is shown as

of a circular form, but can be constructed of any desired shape. The upper part of the shell *j*, is provided with the flange *i*, which is at right angles to the vertical center line of the shell, forming a shoulder of equal width all around the same; this shoulder which rests upon the metal box *k*, provided in the top of the ice-box, supports the shell, and is secured to the metal box in a well known manner.

The shell of the ice-receptacle, is of a conical form and is open at the bottom for the easy escape of the melted ice from same. This peculiar form is given to the lower part of the shell so that the ice cannot fall through the same, but as it melts will move downward and become more packed, and it is my intention in some case of refrigeration in my ice-box, to mix salt with the broken pieces of ice, thereby permitting of a greater degree of refrigeration in the ice-box than would be the case were the salt not used. The shell can be made of any metal desired of suitable strength, for the purpose required.

The metal box *k*, consists of the bottom *m*, provided with suitable openings through

which the shells of the ice receptacles are introduced, the shoulder *i* of same extending laterally beyond the said openings and resting on the bottom *m* of the box, and supporting the shells. Vertical side pieces *n* are integrally secured to the bottom piece *m* of the box and provided with a flange *l*, all around same, extending outwardly and at right angles to the vertical pieces *n*, which rest on shoulders provided in the upper edges of the ice-box as shown. The metal box can be made of any suitable depth desired and can be constructed of one piece or of different pieces integrally secured together.

The hinged door *B* is provided in the top of the ice-box as a cover over the metal box and ice receptacles, when the ice-box is closed and as an easy means of access for removing same, for cleaning, etc.

It is obvious that my improvement can be somewhat differently arranged and constructed as herein described without departing from the principle of my invention.

Having described my invention what I claim as new and desire secured by Letters Patent is:

In an ice-box or refrigerator a plurality of removable conical shaped ice receptacles provided with supporting flanges around the outer upper edges of same, the lower ends being open, a removable catch basin having a horizontal, perforated bottom provided directly under said ice-receptacles, the bottom of the ice box being inclined and connected at its lowest point with a drain pipe, all as described and for the purpose intended.

GUSTAV J. GRUENDLER.
